UNITED STATES PATENT OFFICE.

NICOLAS EMILIE MÉTHLIN, OF PARIS, FRANCE, ASSIGNOR TO SCHNEIDER & CIE., OF PARIS, FRANCE, A LIMITED JOINT-STOCK COMPANY OF FRANCE.

TORPEDO TUBE COMBINED WITH MEMBERS FOR STARTING AND SETTING THE TORPEDO CONTAINED THEREIN.

Application filed May 3, 1926, Serial No. 106,559, and in France June 25, 1925.

It is known that torpedoes comprise a certain number of members such as the air retaining valve and the gyroscope which, once the torpedo is placed in position in the 5 torpedo tube installed in a submarine or other vessel must be adapted to undergo a change of position or a setting from the outside by means of keys or other similar devices engaging through the tube and entering into the torpedo. These controlling or setting keys must be withdrawn or move out of the way automatically when firing takes place.

Now, in installations at present in use, 15 the possibility exists of forgetting to open or set these members. If the air retaining valve has not been opened it is quite possible to discharge the torpedo from the torpedo tube but, as its engine is not supplied, 20 it will stop. Similarly, of the inclination of the axis of the gyroscope has not been adjusted, or has not received the required setting the torpedo will travel in a false direction.

25 According to the invention such accidents are rendered impossible on account of a conjugation between these starting and setting or adjusting members on the one hand and a movable essential member of the torpedo 30 tube on the other hand, the conjugation being such that the tube is not ready for the launching operation unless the keys have been previously moved into the desired position in order to effect the starting and setting operations. In practice, the essential 35 member of the torpedo tube is preferably the breech door, the conjugation with the keys being such that the breech can only be closed when the keys have all been placed.

40 The invention comprises a particular form of construction in which the keys are arranged in such a way that their axes can be made not to coincide exactly with the axes of the catches in which they have to engage 45 for the purpose of controlling the valve or setting the gyroscope.

Mechanical connecting means with the front door of the tube or any other member the movement of which is conjugated with 50 that of this door will effect, according to a known principle, the withdrawal of the keys or other controlling or adjusting members,

while the opening movement of the said door takes place, so that the torpedo will be free to travel through the tube at the 55 moment of discharge.

Finally, in the case when a torpedo is to be removed from its tube for inspection purposes or for any other reason, an additional device, conjugated with the opening movement of the door of the breech is provided 60 in order also to produce, according to the invention, the withdrawal of the keys thus enabling the torpedo to be freely withdrawn through the rear opening of the tube without any risk being run of damaging the torpedo itself or the said keys. This device operates in the same way when a torpedo is being placed in the tube.

A practical constructional example of the 70 invention is illustrated in the accompanying drawings, in which:

Figures 1 to 19 show in full lines the manner in which one single operating or setting key (for example the key for adjusting or 75 setting the gyroscope) is arranged so as to be in operative relationship with the device for closing the breech; operative relationship at the same time with other keys being obtained, as shown in Figures 21 and 22, 80 by essentially similar means.

Figures 1 and 1^A show in elevation, a torpedo tube of present day type, provided with the new device for producing its operative relationship with the gyroscope setting key. 85

Figures 2 and 2^A are corresponding views in plan.

Figure 3 is a section to a larger scale, through the tube, across the casing of the mechanism associated with a key, taken 90 along the line 3—3 in Figure 1^A.

Figure 4 is a detail to a larger scale, of a part of the arrangement shown in Figure 3.

Figures 5 and 6 are sections taken along 95 the lines 5—5 and 6—6 in Figure 4 respectively.

Figures 7 and 8 show, in elevation and plan, the safety mechanisms, the door of the breech being shown open.

Figures 9 and 10 are corresponding elevations, the door of the breech being closed.

Figure 11 is a plan view of the safety devices, the door of the breech being in an

intermediate position between its open and closed positions.

Figures 12 and 13 are detail views, to a larger scale, of the movable end of the operating lever.

Figures 14 to 19 are diagrams showing the positions of the mechanisms for the various stages of working.

Figure 14 shows the position of the members when the torpedo is to be placed in the tube, the front door being closed, the door of the breech open and the key withdrawn.

Figure 15 shows the torpedo placed in the tube, the front door being closed; the door of the breech open and the key in its catch or lodgment.

Figure 16 shows the torpedo placed in the tube, the two doors being closed and the key in place.

Figure 17 shows the positions occupied by the members when the torpedo is launched; front door open, breech door closed, key withdrawn.

Figure 18 shows the position occupied by the members after the torpedo has been launched; tube empty, both doors closed, key withdrawn.

Figure 19 shows the tube with or without torpedo; front door closed while the screw-threaded ring is being rotated in order to open the door of the breech.

Figure 20 is a diagram showing the arrangement for distant control; below deck in surface craft or within the resisting shell in a submarine.

Figures 21 and 22 show diagrammatically in elevation and plan respectively the controlling or operating device for a second member of the torpedo.

In these various figures: A^1 is a fluid tight torpedo tube, of present day type, with a front door A^2 and a breech door A^3 , the arrangement of which is known, and which is provided with indentations (Figs. 7 and 9), and kept closed by a screwthreaded ring A^4 provided with corresponding indentations or notches.

The front door A^2 of the tube A^1 is operated in a known manner, for example by means of a hydraulic motor A^5 (Fig. 1) in which a fluid under pressure, actuating, a rod A^7 and a lever A^8 by means of a piston A^6 , causes the door to turn upon its hinge pin A^9 . The fluid when the door is fully open, acts in the known manner in the interior of a cylinder Q , which controls the movement of the locking pin O , releasing the torpedo, and thus enabling the latter to be discharged.

The other accessory members of the tube such as valves, inspection doors, the necessary safety devices, are not shown in order to simplify the drawing.

C is the body of the casing of the mechanism controlling and operating one of the

keys adapted to bring a member of the torpedo, such as the air retaining valve or the axis of the gyroscope, into the convenient working position. This casing is rigidly mounted upon the tube.

As a result of the amounts of clearance and tolerance provided for in the construction, the member to be actuated does not occupy an unvarying position relatively to the reference or given points of the tubes, (rear face or edge, bearing face of the torpedo guide upon its locking pin or stop, etc.). It therefore happens that the axis of the path along which the key is guided in the tube will not always coincide with the axis of the catch or the like provided in the apparatus to be acted upon and it will in this case be impossible, if the key is formed in one single piece, to make it enter its lodgment.

According to the invention the key is divided into two parts c^1 and c^2 (the key properly so-called and its rod). c^1 is the movable part of the key entering into the member T to be adjusted; c^2 is the part of the key upon which the controlling mechanism exerts its action, the geometrical axis of which part preserves an unvarying direction; this member cannot move in a longitudinal direction except along this axis.

The two parts c^1 and c^2 are connected to each other by the central disc or plate or the like c^3 of a coupling of the Oldham type in which the keys are advantageously replaced by rollers c^4 in order to reduce the frictional forces. A guide c^5 enables a movement of the part c^1 to take place, compatible with the tolerance and clearance provided, but effectively connects the various parts c^1 , c^3 , c^4 together and prevents them from making any movement in a longitudinal direction relatively to each other.

The end of the key proper c^1 which enters into the torpedo is provided with a bevelled portion which abuts against a corresponding sloping portion of the catch or the like formed upon the member T which is to be actuated, which action compels the key c^1 , pushed by the rod c^2 , to move in a direction parallel to its axis and to enter into T .

The shaft c^2 of the key is adapted to be displaced, in the direction of its axis, by a forked lever d^1 secured to and actuated by a shaft D which moves it through the medium of two spurs or projections d^2 , d^3 provided upon a ring d^4 adapted to turn upon the said rod c^2 . The end of c^2 comprises a lodgment c^6 for the purpose of receiving a hand operated key which is inserted through an aperture formed in the casing C , which aperture is normally closed by a plug or cap c^7 .

Further, the shaft c^2 of the key is adapted to be given a movement of rotation by a driving shaft E^1 E^2 through the medium of two toothed wheels e^1 , e^2 .

The wheel e^1 in which c^2 slides without

turning is carried in a bearing formed upon the casing C and secured by a nut e³. The wheel e¹ drives c², for example through the medium of a polygonal joint. The driving shaft comprises two parts E¹, E² connected by a coupling E³ of known type which enables the two parts E¹, E² of the said shaft to be turned through a given angle relatively to each other for the purpose of adjustment. The end of the part E² away from the coupling E³ leads, according to the case, either to the casing F¹ of a bearing indicator of known type (Figs. 1, 2, 7, 9) or a simple hand lever F² (Fig. 20).

The shaft D controlling the longitudinal displacement of the shaft c² may be supported at one end by the casing C, at the other end by a suitable bearing a; it receives its movement, for example, through a transmission arrangement formed by levers and links d⁵, d⁶, d⁷, actuated, for example, by a hand lever d⁸, pivotally mounted upon a pin d⁹ carried in a bearing d¹⁰, and adapted to move to either side of the vertical plane passing through the axis of the pin about which it turns (Figs. 7 and 9).

The hand lever d⁸ is connected by means of a pin d¹¹ to a transverse rod G supported in two seats g¹, g² mounted upon the tube A¹, the said rod serving, as will be seen hereinafter, as a member for obtaining operative relationship with an essential movable member of the torpedo tube such as the breech closing ring A⁴.

The rod G is provided with two spurs or projections g³ and g⁴.

The spur g³ is adapted to come into engagement with the arm h¹ of a bell crank lever h¹—h² turning upon a pin h³ carried upon the tube A¹; the second arm h² of this lever is adapted to effect the movement of a locking pin h⁵, guided in a bearing h⁶ mounted upon the tube A¹, by means of an oval shaped eye and a projecting end or stud h⁴.

The arm h¹ is extended in a finger h⁷ turning upon a pin h⁸ in the plane of the arm. This movement of h⁷ can only take place in one direction (from right to left, Fig. 12); the plane face of h⁷, by abutting against the bottom of the notch or recess in h¹ compels h⁷ to move in the other direction so as to place itself in alignment with h¹ without it being possible for it to pass beyond this position. A special device, described hereinafter, moves h⁷ back into its normal position at the proper time, when this member has been displaced. The stroke of h¹ is limited by the projection g³ and a stop h⁹ formed upon the tube.

The projection or spur g⁴ may, on its side, come into engagement with the arm i¹ of a second bell crank lever i¹—i² turning about a pin i³ also mounted upon the tube; the arm i² of the lever is pivotally connected at

i⁵ to a rod i⁴ pivotally connected at the other end, at i⁶, to a lever i⁷ adapted to pivot about a fixed point i⁸ and pivotally connected by means of a pin and slot to the end of the piston A⁶ of the press A⁵.

The rod i⁴ transmits the movement of the piston A⁶, reduced in a given ratio, to the end i⁵ of the arm i² of the bell-crank lever i¹—i². On the other hand, the screwthreaded ring A⁴ which forms a movable nut for closing the breech, is provided with two stops k and K¹, arranged in convenient positions and adapted to come into engagement, the one k with the movable end h⁷ of the arm h¹ of the double lever h¹—h² when the movements for opening the breech take place, the other K¹ with the locking member h⁵ actuated by the arm h² when the movements for closing the breech take place.

Finally, upon the tube A¹ is mounted a small rocking lever n¹—n² turning about a pin m, the movement of which rocking lever is limited by the projecting pieces m¹—m².

This rocking lever is provided for the purpose of bringing the end or finger h⁷, previously deflected by the stop k, back again into alignment with h¹ under the action of the same stop.

The operation of the device is as follows:

When a torpedo is placed in the tube, the members provided or formed upon the latter occupy the positions shown in Figure 14; the front door A² is closed, the breech door A³ is open, and the key c¹ has been automatically withdrawn as a result of the opening of the door of the breech.

Under these conditions the transverse rod G is thrown back to the right of the tube, the arm h¹ of the bell crank lever h¹—h² is in engagement with the projecting piece or spur g³ of G; the front door being closed, the rod i⁴ is pushed backwards; the end of i⁴ is not in engagement with g⁴. The stop k is behind the movable finger h⁷; the stop K¹ is behind the locking member h⁵.

When the torpedo has been placed in position it is impossible to complete the closing of the door of the breech by rotating the ring A⁴ unless the key c¹ has been moved into position. In fact during the movement of rotation of the screwthreaded ring A⁴ for the purpose of closing the door, if the key c¹ is in a withdrawn position (Fig. 14), the stop K¹ will abut against the locking pin h⁵ which will prevent the screwthreaded ring A⁴ from turning through the requisite angle in order to complete the closing the breech. The door of the breech not being completely closed, it is impossible to launch the torpedo by known devices not shown.

If on the contrary the key c¹ has previously been moved into position by acting

upon the lever d^8 this movement will have driven the rod G towards the left of the tube (Fig. 15). Under the action of the lever h^1 which is in engagement with the projection or spur g^3 provided upon G, the arm h^2 has carried backwards the locking member h^5 thus allowing the stop K¹ to pass. The screwthreaded ring A⁴ may then be completely rotated and the breech thus closed (Fig. 16).

During the movement of the screwthreaded ring, the stop k encounters the finger h^7 of the arm h^1 . As this arm abuts against a projecting part h^9 of the tube the finger h^7 is made to turn about h^8 and allows the stop k to pass. The finger h^7 , during its movement of rotation, raises the end n^1 of the rocking lever n^1-n^2 ; the latter pivots about m and abuts against the projecting piece m^1 ; the stop k, continuing its movement, encounters the other end n^2 of the rocking lever, which had been driven backwards, and pushes it forward again, bringing n^1 into its original position.

During this movement the end n^1 makes contact again with the finger h^7 and brings it back into alignment with the arm h^1 by a fresh pivotal movement about h^8 ; the stop k will therefore be able to carry along h^7 during the movement of the screwthreaded ring for opening the breech.

The door of the breech being closed, firing may be proceeded with by admitting fluid into the press A⁵ for this purpose. As a result of the push exerted by the piston A⁶, through the medium of the link A⁷ and the lever A⁸, the front door A² turns about its hinge pin A⁹. The piston A⁶ carries along the lever i⁷ which in its turn carries along the arm i² of the lever i¹-i², through the medium of i⁶, i⁷, i⁸ (Fig. 17).

The arm i¹ of this lever, through the medium of the spur g⁴ forces the rod G to move towards the right. This movement is transmitted, by the pin d¹¹ to the lever d⁸, and by means of d⁷-d⁶-d⁵ to the shaft D. The rotation of D provokes that of the forked lever d¹ and consequently the withdrawal of the whole of the members c¹, c², c³, c⁴, c⁵ forming the key, so that the passage is left free for the torpedo.

After the torpedo has been launched, during the movement for the closure of the front door, the transverse rod G undergoes no action and remains stationary, the key therefore remains withdrawn. Only the lever i¹-i², actuated by the lever i⁷ and the rodding i⁶, i⁷, i⁸, has moved, and the arm i¹ of this lever, releasing the spur g⁴, takes up its normal position again (Fig. 18). When the next torpedo is to be placed in the tube, the rear door is opened, the parts then taking the position shown in Fig. 14, and the operation continues as hereinbefore described.

In the case when, the torpedo being in the

tube, the key engaged in position, there is need to remove the torpedo, the key will be automatically withdrawn when the screwthreaded ring is rotated previous to opening the door of the breech. In fact during this movement the stop k encounters the finger h^7 upon the lever arm h^1 . As this finger cannot be withdrawn, since its plane face abuts upon the base of its lodgment, the arm h^1 is carried along by k; the rod G follows in the movement of h^1 on account of the presence of the spur g^3 , the lever d^8 is carried along by d^{11} and the transmission system d^7 , d^6 , d^5 actuates the shaft D and the lever d^1 ; the key c¹ is thus disengaged (Fig. 19).

The torpedo can therefore be taken out and replaced in position: it is however, necessary to reengage the key before closing the door of the breech, the movement of rotation of h^1-h^2 having caused the locking pin h^5 to move forward, which pin, if this operation were not performed, would stop the screwthreaded ring by abutting against the stop K' of the latter.

It has been assumed that the withdrawal of the key at the moment of launching the torpedo would be obtained by the opening movement of the front door, by means of rodding directly connected to the press controlling the movement of this door; but the connection may be indirect; it will be understood that the lever i¹-i² may equally well, by means of suitable rodding, be connected to any member of the tube, which is arranged so as to be in operative relationship with the front door.

A modified form, of this nature, is shown, with a part in dot-and-dash lines, in Figures 1^A, 2^A and 3.

O is the pin for locking the torpedo in the tube and is controlled and operated by a press Q through the medium of a link q¹ and a two armed lever o¹, o², pivoting about a pin o³ carried by the casing of the locking or securing pin O. A spring q² tends to drive the pin O into the interior of the tube. The lever o² is connected, by a rod p¹ pivotally mounted at p⁴ upon o², to an arm p³ of the lever i¹-i² upon which it is pivotally mounted at p².

The press Q is arranged so as to be in operative relationship with the press A⁵ in such a way that the motive fluid only enters Q when the piston A⁶ of the press A⁵ is at the end of its stroke and the front door is open.

The operation is as follows:—

When the tube is ready for launching, the locking pin O is pressed upon the torpedo by its spring q², the rod p¹ drawn back and the lever arm i¹ in engagement with the spur g⁴ upon the rod G.

At the moment launching takes place, the fluid, having acted in the press A⁵, enters

the press Q, pushes the piston of this press back and, by the movement of the levers o^2 , o^1 , raises the locking pin O, thus releasing the torpedo. During this movement 5 the lever o^2 by means of its pivot p^4 , the rod p^1 which has been pushed forward, the pivotal connection p^2 and the arm p^3 , has actuated the lever i^2 — i^1 the second arm of which i^1 , by means of the spur g^4 , has carried 10 along the rod G thus provoking the withdrawal of the key c^1 .

After the torpedo has been launched the spring q^2 , compels the locking pin O to re-enter into the tube, drawing the rod p^1 forward. This movement does not affect the 15 rod G so that the key c^1 remains withdrawn and the tube is ready to be loaded with a new torpedo.

In the example shown in Figures 1 to 19 20 the invention has been illustrated in its application to the control and operation of one single member such as the key c^1 — c^2 provided for the purpose of setting or adjusting the gyroscope; but it is obvious that 25 the new device may be employed for the control of a varying number of members. For instance the movements for the withdrawal and placing in position of a series 30 of members may be placed under the control of one and the same transverse rod G. In this way the key for operating the air retaining valve may be connected to the transverse rod G in addition to the gyroscope setting key.

35 Figures 21 and 22 show the arrangement of the additional members mounted upon the torpedo tube and adapted to be in operative relationship with the rod G, which members serve for the control of the said 40 second key. In these figures C¹ is a casing similar to the casing C shown in Figure 4, in which moves the key C² similarly to the key c^1 — c^2 shown in the same figure, and provided for the control and operation of 45 the air retaining valve. E is the shaft through which the movement of rotation is obtained. D¹ the shaft through which withdrawal is effected, which is similar to the shaft D shown in Figures 1 to 19; this 50 shaft D¹ is carried in two bearings such as t^1 — t^2 .

The shaft D¹ is provided at one end with a lever t^3 connected to the key by a ring t^4 provided with trunnions and at the other 55 end with a simple lever t^5 pivotally connected at t^6 to the rod G hereinbefore described. The pivot t^6 moves in oval shaped slots formed in a strap t^7 provided upon the rod G.

60 It is seen that when the rod G is pushed to the end of its stroke towards the right, the key or C¹ is withdrawn and that it will engage inside the tube for any movement of G towards the left, which 65 movement is similar to that of the key c^1 — c^2

of the casing C. Two or more keys will answer, always in the same direction, to any movement of the rod G, whether this movement is obtained by hand operation through the hand lever d^8 or through the 70 action of the various levers h and i ; they will be withdrawn or will engage with the members to be controlled or operated simultaneously.

d^8 is a clutch coupling enabling the two 75 parts of the shaft G to be separated in order to obtain the individual adjustment of the apparatus C¹.

The movement of rotation for each of the keys or other similar members may be 80 obtained through suitable means of transmission from any point on the vessel.

Figure 20 shows diagrammatically by way of example an arrangement in which the pinion e^2 shown in Figure 4 is controlled and actuated from the interior of a 85 submarine.

Claims:

1. In combination with a torpedo tube having a movable member, means to adjust 90 the torpedo mechanism and operative connections between said means and said member, movement of said member to operative position being prevented when said means are in inoperative position.

2. In combination with a torpedo tube, a movable member operable before firing, means to adjust the torpedo mechanism, and operative connections between said means and said member to actuate said 100 means to inoperative position when said member is moved to inoperative position and to prevent movement of said member to operative position without prior movement of said means to operative position.

3. In combination with a torpedo tube having a door, means to adjust the torpedo mechanism, means to lock the torpedo in the tube, and means operatively connecting said door with said adjusting means and said 110 locking means to withdraw both of said means from operative position.

4. In combination with a torpedo tube having a pair of doors, means to control the torpedo in the tube, and means operatively 115 connecting said controlling means with said doors, the opening of either door withdrawing said controlling means from operative relation with the torpedo.

5. In combination with a torpedo tube 120 having front and rear doors, means to control the torpedo in the tube, means actuated by movement of the rear door to open position to operatively disconnect said controlling means from the torpedo, and means 125 actuated by movement of the front door to open position to disconnect said controlling means from the torpedo.

6. In combination with a torpedo tube having a plurality of members, means to 130

control the torpedo in the tube, means operatively connecting said controlling means to said members, and means to operatively connect said controlling means with the torpedo, and the movement of either of said members being adapted to retract said controlling means from such operative connection.

7. In combination with a torpedo tube having a plurality of members operable before firing, means to control the torpedo in the tube, manually operable means to operatively connect or disconnect said controlling means with or from the torpedo, and means actuated by movement of one of said members to firing position to disconnect said controlling means from the torpedo.

8. In combination with a torpedo tube having a member operable before firing, means to control the torpedo in the tube, and means operatively connecting said controlling means with said member, said last named means preventing the operation of said member when said controlling means are in inoperative relation with the torpedo.

9. In combination with a torpedo having front and rear doors, means to control the torpedo, manually operable means to operatively connect or disconnect said controlling means with the torpedo, and means operatively connecting said controlling means with said doors, the closing of the rear door being prevented by said connecting means when said manually operable means are in inoperative position, and the opening of either door being adapted to withdraw said controlling means from operative relation with the torpedo.

40 10. In combination with a torpedo tube having a rear door, means to control the torpedo in the tube, a bar slidably mounted on said tube and operatively connected with said controlling means, movement of said bar actuating said means into operative or inoperative position, and means operatively connecting said bar with said rear door.

45 11. In combination with a torpedo having a rear door, means to control the torpedo in the tube, a bar slidably mounted on the tube and operatively connected with said controlling means, manually operable means

for actuating said bar, and means operatively connecting said bar with said rear door.

55 12. In combination with a torpedo having front and rear doors, means to control the torpedo, a reciprocable bar on said tube operatively connected with said means, means for manually moving said bar, and means operatively connecting said bar with said doors, the movement of either door to open position actuating said bar to withdraw said controlling means from operative relation with the torpedo, and means operatively connected to said bar preventing the closing of one of said doors when said controlling means are in inoperative relation with the torpedo.

60 13. In combination with a torpedo tube having a plurality of movable members, means to control the torpedo, a slidable bar operatively connected to said controlling means, manually operable means for moving said bar, stop members on said bar, and means including a plurality of levers operatively connected to said movable members and adapted to engage said stop members to actuate said bar with movement of said movable members.

65 14. In combination with a torpedo tube having a movable member, means to control the torpedo, lever means operatively connected to said controlling means to operate the same, and a one-way collapsible member on said lever means adapted to be engaged by said movable member whereby operation of said movable member in one direction does not actuate said controlling means.

70 15. In combination with a torpedo tube having a movable member, means to control the torpedo, and means including a plurality of levers operatively connected to said controlling means to operate the same, one of said levers being adapted to be interposed in the path of said movable member when said controlling means are in inoperative relation with the torpedo to prevent movement of said movable member to firing position.

75 In testimony whereof I have signed this specification.

NICOLAS EMILIEU METHLIN.
